BOW FOR STRINGED INSTRUMENTS

Albert Matha, Chicago, Ill.

Application November 7, 1935, Serial No. 48,709

6 Claims. (Cl. 84—282)

My invention relates to bows for violins and similar string instruments, wherein the fine hair-like steel or metal strings are removably secured to the bow-tip and the frog by suitable means which will firmly hold the strings in place and 5 also permit quick removal and replacement when occasion requires, without, however, adding any material and undesirable weight to the bow.

My invention has for its object the provision of means whereby the grouped strings will be 10 firmly held in position against the bottom surfaces of the tip and of the frog of the bow without, however, subjecting the strings to improper action or strains; the string holding means being such that the usual bow-tip and bow-frog constructions 15 may be employed.

The objects of my invention and its inherent advantages will all be readily apparent from the detailed description of the accompanying drawings 20 wherein:

Figure 1 is a perspective view of a bow with an intermediate portion broken away and showing my invention.

Figure 2 is a detail view in side elevation of the frog end of the bow with a portion of the frog shown in section to illustrate the fastening means at the rear end of the group of strings.

Figure 3 is a sectional view of the frog end 25 of the bow, taken on the line 3—3 of Figure 2.

Figure 4 is a detail cross-sectional view taken 30 substantially on the line 4—4 of Figure 3 as viewed in the direction of the arrows.

Figure 5 is a detail perspective view of the bow-tip and string fastening means.

Figure 6 is a side elevation of the bow-tip with 35 a portion of the tip and the string fastening means in section.

Figure 7 is an elevation of the nose of the bow-tip and of the string fastening means.

Figure 8 is a sectional view taken substantially 40 on the line 8—8 of Figure 6 as viewed by the arrows.

Figure 9 is a sectional elevation of a portion of the frog and showing a modification.

The invention consists of improved means for 45 removably securing the strings to the conventional violin bow, the staff 10 whereof terminates at its forward end in the slightly upwardly sloping tip 11, while the rear or finger grasping end is provided with the frog 12 which is adjustable in a 50 direction longitudinally of the staff 10 and controlled by the usual screw with the finger grasping head or end piece 13. As the frog mounting and frog controlling means is of a well known type and forms no part of my invention further

detailed description thereof need not be entered into.

My improved means contemplates the use of metallic strings, preferably steel hair-like wire or strands 14, in suitable number. The forward 5 ends of the wires or strands 14 are secured, preferably by soldering, to what may be termed the inner or top face of the flat plate portion of the bow toe or tip engaging member or yoke 15. Securing the ends of the strings to the toe engaging 10 face of the plate portion of member 15 leaves the lower exposed side without a possible rough surface; then too a more secure fastening of the strings may be obtained by fastening the strings 14 around the forward edge of the plate portion 15 as more clearly shown in Figure 5; and at the same time the strings are all caused to lie or extend flush with the lower face of the plate portion and held in proper position when the strings are placed under tension.

The forward end of the plate portion of member 15 and at opposite edges is provided with the strap-like portions 16, 17, which are intended to 20 extend about the tip 11 of the bow.

The member 15 is preferably made of thin 25 sheet metal of a type which is very light so as to add no perceptible weight to the tip of the bow. One of the strap portions, for example the strap 16, is shown with a slightly enlarged end which is provided with a slit at 18 which is adapted to 30 receive the narrow end of strap 17 as shown in Figures 7 and 8; the inserted end of the strap 17 is then bent back upon itself beneath the enlarged portion of strap 16, where it will lie against the tip and hence prevent all possibility of being 35 pulled out of slit 18 when the strings 14 are placed under tension. At the same time it is apparent that the straps 16 and 17 in conjunction with the plate portion provide a yoke member which may be readily slipped onto or off the 40 toe or tip of the bow when it is desired to apply or remove the strings; it being, of course, necessary to release the tension on the strings before it is possible to release the yoke straps from the tip of the bow.

The rear ends of the strings are all properly secured—as by solder—to a thin and flat metal piece or plate 19; the plate being very light metal and the ends of the strings all secured to one face of the plate. This plate is preferably provided 50 with tapered side edges as shown in Figure 3; that is to say, the plate becomes narrower toward the forward end of the plate.

The plate 19 is removably held by the side flanges 20, 20 of an attaching member 21 which 55

is adapted to extend flush with the lower face of the frog 12 of the bow; the side flanges 20, 20 being bent over the upper face of the member 21 so as to lie against the bottom of the frog.

5 The forward end of member 21 with its flanges 23, 23 is formed with a taper toward the front end so that the open sided pocket formed by the flanges 20, 20 becomes narrower toward the front and hence wedgingly holds the string end plate 19 against forward movement. When the tension on the strings 14 is sufficiently released through proper manipulation of finger screw member 13, the string plate 19 may then be slid rearwardly from beneath the flanges 20, 20 and 15 thus permit renewal of the strings should occasion require without the necessity of renewing or removing the attaching member 21.

The rear end of member 21 is bent upwardly upon itself as shown at 22 thereby providing a 20 channel or space between the overlapping end 22 and the body of member 21 to receive the tie wire or loop 23 which is adapted to extend about the rear end of the frog 12 of the bow; the loop 23 being of less transverse dimension than the 25 bottom of the frog 12 so as to fit the narrower portion of the frog 12 and not be permitted to slip down and off the frog as is apparent from Figure 1.

20 The overlapped end 22 of plate or member 21 is slotted as shown at 24 in Figure 3 for passage of the small pin 25 which is driven into the frog 12; the head of the pin 25 being disposed between the overlapped end 22 and the body of member 21 and preferably slightly larger than the width 35 of the slot 24 to assist in holding the member 21 up against the bottom of the frog 12.

With the pin 25 arranged adjacent the rear end 40 of the member 21 as shown, the member 21 is permitted to slightly swing or pivot about the pin 25 toward one side in the event of any slight inaccuracy in string-length at opposite sides of the group, thus tending to place all of the strings under substantially the same degree of tension.

Figure 9 is a detail sectional view of a part 45 of a frog 12^a and a string plate or end holding member 21^a which is formed exactly like member 21 except that the overlapped rear end 22^a is not slotted and the frog 12^a is not provided with the pin 25. The member 21^a, like in the previously described construction, is removably secured or 50 held against the lower face of the frog by the band or wire loop 23.

With my improved means the strings will be 55 firmly and uniformly held against any improper pivotal or oscillating movement, while permitting an amount of self adjustment.

As is apparent from the constructions shown, 60 the strings and string-holding clips or members may be easily removed and replaced should occasion require; the renewal or replacement being readily accomplished without need for special skill or tools.

Then too, instead of the metallic strings, horse-hair may be used as the ends of the latter may 65 also be secured to the thin metallic plates or terminals and the latter removably secured to the bow-tip and to the frog of the bow; the invention residing in the fastening means or elements for holding the strings removably in place; and 70 while the constructions shown and described are believed to be the best embodiments of the invention, modifications are possible and may be made without, however, departing from the spirit of my invention.

75 What I claim is:—

1. In a bow for string instruments, bow-strings whose opposite ends are fixedly secured to thin metallic plates, the plate at one end being provided at opposite edges with bow-tip encircling extensions whose free ends are formed to have 5 interengaging relation; a flat member adapted to extend flush with the bottom of the frog of the bow and formed to provide an exposed smooth surface and provided with an open-ended pocket adapted to receive the plate secured to the rear 10 ends of the strings while the strings extend through the open end of the pocket; and means pivotally secured to the member whereby the latter is removably secured to the frog.

2. In a bow for string instruments, bow-strings 15 whose opposite ends are fixedly secured to thin flat plates, one of the plates being provided at its forward end at opposite edges with adjustable bow-tip encircling extensions formed to have tongue and slot interengaging relation; a member adapted to extend flush with the bottom of the frog of the bow and provided at its forward end with an open-ended pocket disposed lengthwise of the frog and adapted to receive the plate secured to the rear ends of the strings; and a 20 yoke member pivotally secured to the rear end of the member and adapted to encircle the rear end of the frog for removably securing said first member in place.

3. In a bow for string instruments, bow-strings 25 whose opposite ends are immovably secured to flat sheet metal plates, the plate at one end being tapered toward one end while the plate at the other end has a pair of forwardly disposed integral extensions adapted to extend about the tip 30 of the bow, the one extension having an aperture to receive the end of the other extension, whereby the strings are removably secured to the bow-tip; a sheet metal member adapted to extend flush with the bottom of the frog of the bow, the 35 forward end being formed to provide an open-ended pocket tapering toward the forward open end and adapted to slidably receive the string holding tapered plate through the rear end of the pocket; and a yoke member pivotally secured 40 to said sheet metal member and adapted to extend about the rear end of the frog of the bow for removably securing the strings to the frog.

4. In a bow for string instruments, the combination with the bow having a tip at one end and an adjustable frog at the other end; a plurality of strings; a tip engaging flat plate to which the forward ends of the strings are immovably secured, said plate at opposite side edges 55 having integral forwardly and upwardly disposed extensions adapted to extend across the forward nose of the tip, the ends of said extensions being formed to have interengaging relation with each other and adapted to hold the plate portion with 60 the attached strings in non-twisting relation with the bottom of the bow-tip; a tapered flat plate to which the rear ends of the strings are secured; a plate holding member disposed on the lower face of the frog with its forward end tapered 65 and the side marginal portions bent back upon the member to provide a tapered plate receiving open ended pocket while the rear end of the member is substantially coextensive with the width of the bottom face of the frog and folded back upon itself; and a loop pivotally held at 70 one end between the folded back portion of said plate holding member while the other end is adapted to fit about the rear end of the frog and 75

the member with said tapered plate held against the bottom of the frog.

5. In a bow for string instruments, a plurality of strings, a flat plate to which the forward ends of the strings are fixedly secured, the forward opposite edges of the plate having forwardly and upwardly extending strap portions adapted to fold about the nose of the bow-tip with the ends of said portions formed to have interlocking relation with each other; a flat tapered plate to which the other ends of the strings are fixedly secured; a flat plate holding member disposed along the bottom of the frog of the bow, the forward end being formed to provide a forwardly 10 tapered pocket adapted to hold said tapered plate against the bottom of the frog of the bow; and a link pivotally secured to the rear end of said member and adapted to extend about the rear end of the frog and to maintain the member 15 substantially parallel with the frog.

6. In a bow for string instruments, a plurality of strings, terminal plates to which the ends of the strings are fixedly secured, the terminal plate at the forward ends being substantially co-extensive with the width of the tip of the bow 5 and provided at opposite edges with integral and upwardly disposed pliable extensions adapted to pass about the forward part of the tip and the ends of said extensions formed to have inter-engaging relation, while the terminal plate at the rear ends tapers forwardly; a fastening member provided at its forward end with an open ended forwardly converging pocket; adapted to slidingly receive said tapered terminal plate, the rear end of said fastening member having a swiveled loop 15 adapted to extend along opposite sides and about the rear of the frog of the bow so as to effect a uniform rearward pulling action on the string terminal member.
